BOX COVERING MACHINE

William Russell Redd, Western Springs, Ill., assignor to Wm. Wrigley Jr. Company, Chicago, Ill., a corporation of Delaware

Application September 23, 1938, Serial No. 231,353

8 Claims. (Cl. 93—55)

This invention relates to a machine for covering boxes, and consists of the matters hereinafter described and more particularly pointed out in the appended claims.

5 The boxes are of a familiar type, made of paper or cardboard, open at the top and comprising bottom, side and end walls. They are to be covered by lids of the same form but of slightly larger dimensions, so that the lid may be telescoped upon the box. Boxes of the kind are sometimes, and as illustrated in this case, provided along one edge with a folding flap or fly, which is generally of such dimensions as to extend part way across the box to partially cover its 10 contents when filled with the merchandise it is to contain.

The general object of the invention is to provide an automatically operated box-closing apparatus, including a conveyor for the boxes, by 20 means of which, a box is brought towards and in a plane below a chute or other device designed to support lids; a lid is ejected or fed from said chute or device and retained in a rearwardly and upwardly inclined position above and proximate to said conveyor; a box, as and when fed on the conveyor, is directed into alignment with said lid and is advanced on said conveyor to engage within said lid, which is telescoped down upon the box and then completely closed thereon, 25 after which the closed box is carried away on the conveyor.

Another object of the invention is to provide, in combination with a conveyor for boxes, an automatic device in association with a stack containing lids disposed in pairs, one above the other, by means of which the lids are discharged in succession into position to be applied to boxes advanced on the conveyor.

Another object of the invention is to provide an improved automatic device by means of which the lids are telescoped in succession down upon boxes advanced on the conveyor.

Another object of the invention is to provide an automatic box covering machine including a chute for supporting lids disposed in pairs one above the other, with the rear end of the top lid of each pair embracing the sides and end of the bottom lid, a main box conveyor to which said lids are delivered in succession into a rearwardly and upwardly inclined position, means by which said boxes are automatically displaced on said conveyor into alignment with said chute, in combination with an auxiliary conveyor movable on said main conveyor and adapted to drive a box

into telescoped relation with a lid discharged from said chute.

These and other objects and advantages of the invention will appear more fully as I proceed with my specification.

In the drawings:

Figure 1 is a side elevation of the improved box-lidding machine.

Figure 2 is a top plan view of the machine with parts upon a somewhat larger scale than that 10 shown in Figure 1.

Figure 3 is a view showing a vertical section through Figure 2, the plane of the section being indicated by the broken line 3—3 of Figure 2.

Figure 4 is a vertical sectional elevation 15 through the driving and control mechanism in a plane indicated by the line 4—4 of Figure 3.

Figure 5 is a view of the main drive and clutch shaft in a section on the line 5—5 of Figure 1.

Figure 6 is a detail sectional view of a clutch 20 engaging and trip mechanism in a plane indicated by the line 6—6 of Figure 4.

Figure 7 is a plan sectional view in a plane indicated by the line 7—7 of Figure 3.

Figure 8 is a sectional view in a plane indicated 25 by the line 8—8 of Figure 7, with parts removed to show boxes in a position slightly forward of the position shown in Figure 7.

Figure 9 is a plan section similar to Figure 7, with the boxes in a position intermediate the 30 position shown in Figures 7 and 8.

Figure 10 is a view similar to Figure 8, with a box approaching the position of the final step in the cycle of operation of the machine.

Figure 11 is a side elevation partly in section as 35 viewed from the rear side of the machine, the part in section being substantially in the plane indicated by the line 11—11 of Figures 2 and 4.

Figure 12 is a detail diagrammatic perspective view to be described more particularly hereafter. 40

Referring to that embodiment of my invention illustrated in the drawings: 20 indicates a table upon which is supported a conveyor belt 21 traveling in the direction of the arrow 21a. (See Fig. 1.) The table is supported upon a frame 45 structure comprising longitudinally spaced uprights 22, 22 and laterally spaced side members 23, 23. (See Figs. 2 and 4.) 24 indicates an upright chute supported by the frame. (See Figs. 1, 3, 8 and 10.) It is designed to contain, in a 50 stack in nested relation, lids 25 (see Figs. 1, 8 and 10) which are to be applied to boxes 26 (see Figs. 7, 8, 9 and 10) when brought in succession below the chute. As shown, the lids which are all of like dimensions, are disposed in the stack in pairs, 55

with the upper lid of each pair inclined downwardly and rearwardly with respect to the lower lid and to the direction of travel of the conveyor, and with its side and rear walls embracing the side and rear walls of the lower lid as shown in Figures 8 and 10.

The chute 24 is made up of four upright angle bars 24^a, 24^b disposed to provide the four corners of an upright rectangular skeleton structure adapted to receive and sustain the nested boxes in stack relation, as shown in Figs. 1, 8 and 10. It is open at the top to receive the lids 25. It is also open at the bottom to discharge the lids, except for a reciprocable, horizontal slide plate 27 (as shown in Figs. 1 and 8) which normally projects rearwardly beyond the forward angle bars 24^a, 24^b in a plane below the stack to present a horizontal support for the forward end of the bottom lid in the stack. The rearward angle bars 24^b, 24^a have their flanges extending transversely of the conveyor cut away somewhat above the level of the slide plate 27, as shown in Figs. 8 and 10; but their other flanges which extend parallel to the conveyor project below the plane of said slide to provide lateral guides for lids when released from the chute by the forward withdrawal of said slide plate 27. Until such withdrawal, the bottom pair of lids as well as the stack of lids above it, is supported by said slide plate 27 and by the engagement of the rear end wall of the top lid of the lowermost pair of lids against the transverse flanges of the rear angle bars 24^b, as shown in Figure 8.

Laterally spaced, rearwardly inclined, fixed arms 29 are disposed below and somewhat rearwardly of the slide plate 27. (See Figures 8 and 10.) An upright guide plate 30 extending longitudinally of the conveyor belt is fixed above said belt. (See Figures 1, 2 and 11.)

Mechanism, presently to be described, is adapted to reciprocate the slide plate 27 forwardly and rearwardly with respect to the direction of travel of the conveyor. Thus said plate is moved from its supporting position below the stack of lids in the chute, as shown in Figure 8, to a non-supporting position as shown in Figure 10. As a result, the bottom two nested lids drop towards the conveyor belt 21. They are guided laterally in their fall by the guide plate 30 (see Figure 3), and are momentarily arrested by a fixed horizontal plate 38 (see Figure 10) upon which their forward ends come to rest in the path of movement of the reciprocable slide plate 27. Upon the rearward reciprocation of the slide plate 27, said plate will strike the front end of the lower one of the pair of lids and eject said pair rearwardly from the chute, as shown at 25 in Figure 8, where their rear ends have come to rest on a downwardly and forwardly inclined plate 32 which extends transversely of the conveyor 21 and is fixed to a frame member 33 above said conveyor. At the same time, the top one of the pair of lids will be struck sharply by laterally spaced rock arms 34 (see Figure 8), and brought to a position rearwardly and upwardly inclined as to the conveyor, with the top lid arrested by engagement at its forward end against the fixed arms 29, and the forward end of the bottom lid close above the conveyor ready to be applied to a box advanced on the conveyor. The lower lid is restrained from following the conveyor by a forwardly and downwardly inclined plate 46 below the plate 32, with upright yielding fingers 50 (see Figures 2, 8 and 10) which stand in position

to engage the rear end wall of said lid. The arms 34 which may aptly be called spanker arms, will remain in contact with the top lid until the lower lid has been applied to and carried away by a box advancing on the conveyor, whereupon they will be returned to the position shown in Figure 10.

The boxes 26 (see Figure 7) to be covered by the lids, as illustrated herein, are provided with foldable flies or flaps 28^a (see Figure 9) which are 10 designed to partially cover the merchandise in the box—in this case packages of chewing gum. To insure close contact of said flies with the box contents and proper settlement of said contents in the box to receive the lid (in case such flaps are not used), the boxes are conveyed through a tunnel 28 (see Figures 4, 7, 8 and 9) having a top wall 28^a disposed for close engagement against the tops of said boxes. Said top wall 28^a has a downwardly and forwardly inclined 15 guiding wing 28^b at its entering end (see Figures 2 and 11) to engage said flies (or the contents of the box) and to fold and hold them down as the boxes approach and enter said tunnel on the way to the chute 24 where the lids are to 20 be applied. Said tunnel also has front and rear vertical side walls 28^c and 28^d which are spaced at a greater distance than the width of the box at the entrance to said tunnel, as shown in Figures 7 and 9. But at the point of immediate approach to the position of the chute 24, the rear side wall 28^d is inclined towards the front wall to bring a terminal end part 28^e into 25 parallel spaced relation to the front wall 28^c, equal to the width of a box. By this arrangement as a box traveling on the belt 21 approaches the chute 24, it is displaced laterally on the conveyor to a position somewhat offset forwardly with reference to said chute.

At the rear side of the table in a horizontal 30 plane close above the belt 21 (see Figures 9 and 10) is located an endless sprocket chain 40 intermittently movable relative to the conveyor belt 21. Said chain is engaged with sprocket wheels 41, 42 which are mounted respectively 35 upon a vertical shaft 41^a and a stud 42^a. It is provided with longitudinally spaced lugs 43 which project laterally beyond and in a plane below a horizontal ramp bar 44 fixed to a frame member in the vertical plane of the forward reach of said chain. 45 indicates a pusher bar (see Figures 7 and 9) disposed for operation in a horizontal plane over against the ramp bar 44 in close relation to the conveyor belt 21 and normally in line with the front side wall 28^c 50 of the tunnel 28 through which the boxes to be covered are conveyed. Said pusher bar is designed to operate after a box has passed the terminal end 28^e of the rear side wall of the tunnel to push a box laterally of the conveyor belt 21 against the ramp bar 44 with its rear end in position to be engaged by a lug 43 on the chain 40. When a box 26 reaches this position and the chain 40 is operated to travel forwardly 55 with respect to the conveyor, the box being guided between the ramp bar 44 and the pusher bar 45, will be advanced in alignment with the chute 24 to receive a lid.

As the box 26 continues to advance, its front end is engaged within the front and side walls 70 of the lowermost lid 25 and the lid is then carried with the box forward relatively to the conveyor 21. And the rear wall of said lid is slipped over the rear end of the box 26 by the yielding fingers 50 on the plate 46, which acts somewhat 75

in the manner of a shoe-horn, to bring the side and rear end walls of the lid into embracing or telescoping relation upon the side and rear end walls of said box.

5 Intermediate the fixed arms 29, 29 are located laterally spaced spring controlled fingers 36 (see Figures 3 and 8) mounted on a transverse shaft 39. Said fingers normally stand in the position shown in Figure 3—each being held in that position by a heel 37 which engages a bar 38^a. In such position they depend into the path of an advancing box with the lid applied, as the box and the lid telescoped thereon are fed along over the conveyor 21 by the auxiliary conveyor 10 15 40. Said fingers bear upon the lid and force it into closed relation on the box. And this action of the fingers is supplemented by depending, free swinging rollers 51, suitably supported upon the frame, which depend into the path of 20 the box, as shown in Figure 8.

Thus as a box is moved over the conveyor 21 by the movement of a lug 43 on the chain 40, it passes successively through the positions shown in Figures 7, 9, 8 and 10—being forcibly advanced 25 on the conveyor by said lug until it passes beyond the rollers 51, as shown in Figure 8, and until said lug is withdrawn from engagement with the rear end of the box by passing about the sprocket wheel 42 (see Figure 9), whereupon the 30 box with its lid closely applied will be carried forward on the conveyor belt 21 alone.

As the lower one of a pair of lids is carried away and applied to a box, as shown in Figures 8 and 10, the upper lid of the pair will drop to the position theretofore occupied by the lower lid; and said upper lid will be applied to a box when it is advanced along the conveyor in the manner heretofore described.

It is to be understood that the advance of boxes on the conveyor to the chute 24 may or may not be continuous. Thus the operation of the lid-releasing and ejecting slide plate 27, of the endless chain 40 with its box-engaging lug 43, and of the box-positioning pusher bar 45, 45 all operated in predetermined timed relation as heretofore described, are dependent upon the advancement of a box into position opposite to a lug 43 on said chain. And as the slide plate 27 releases and ejects a pair of lids, it, as also 50 the spanker bars 34, operates but once for the advance of two boxes in succession by the chain 40. This is controlled by a trip mechanism now to be described, instantly actuated by a box advanced on the conveyor when it reaches a 55 position with its rear end forward of a lug 43 on the chain 40.

At the front side of the conveyor belt 21 and extending parallel thereto (as shown in Figures 7 and 9) is located a longitudinally recipro-
cable trip bar 68, suitably mounted in the frame.
60 Said bar is provided with a transverse shoulder or trigger 69 which extends shortly into the path of the boxes 26 as they are advanced on said conveyor. Said trigger 69 is spaced approximately a box length forward (with respect to the direction of travel of the conveyor) of the terminal end part 28^e of the rear side wall
65 of the tunnel 28.

When the forward end of a box 26 advanced by the conveyor, strikes the trigger 69 and moves the trip bar 68 forwardly to its limit of movement, mechanism hereafter to be described, actuated by the aforesaid bar 68, operates the pusher bar 45 to move the box transversely of the conveyor to release its front end from the

trigger 68 and to bring it into side engagement with the ramp bar 44, with its rear end in position for engagement by the forward side of a lug 43 on the chain 40, as shown in Figure 9. Said chain 40, also operated by the same drive mechanism, immediately moves forward to convey the box over and independently of the conveyor belt 21 toward and below the lids 25 disposed and held against movement with the conveyor, as shown in Figure 8.

We now pass to a description of the power mechanism by means of which the foregoing described apparatus is driven.

A motor 52 (see Figures 2 and 3) is mounted on the frame above the conveyor belt 21 and the operating devices associated therewith. The shaft 53 of said motor extends parallel to the direction of travel of the conveyor belt 21 and is connected through a reduction gearing 54 and a bearing casing 55 to a continuously driven horizontal shaft 56 (see Figures 4 and 5) extending transversely above the conveyor and mounted on frame members 57 in any convenient manner. 58 indicates a rotary drum on said shaft 56. Said drum is adapted to be connected to said shaft 56 by a spring controlled clutch dog 60 (see Figures 4, 5 and 6) mounted on a radial arm 60^a fixed to the said drum. Said clutch dog 60 is located in the vertical plane of, and is adapted for engagement with, one of diametrically opposed teeth 61, 61 of a clutch disc 62 fixed on the shaft 56. 15 20 25 30

On the drum 58 is formed a cam groove 63 (see Figures 4 and 5) in which is engaged an arm 64 fixed to a horizontal stud 65 suitably mounted in a frame-supported bearing 66 with its axis of rotation extending parallel with the direction of travel of the conveyor belt 21 (see Figures 3 and 4). The other end of said stud has fixed to it a depending arm 67 carrying at its bottom end the pusher bar 45, which is movable transversely of the conveyor belt 21, as heretofore described.

The trip bar 68 (see Figures 1, 3, 4 and 7) extends beyond the operating shaft 56 with reference to the advancing conveyor belt 21, and has its end pivotally connected to a rock arm 70 fixed to the front end of a horizontal spring controlled rock shaft 71 mounted in the frame above and extending transversely to the conveyor. At the other end of said rock shaft is fixed a pawl 72 (see Figure 6) adapted for engagement with a heel 73 on the spring controlled clutch pawl 60. By this mechanism, when the forward end of a box engages the trigger 69 and in its advance with the conveyor moves the trip bar 68 (from the position shown in full lines to the position indicated in dotted lines in Figure 7), the pawl 72 releases the heel 73 and allows the spring controlled clutch pawl 60 to engage a tooth 61 of the clutch disc 62 rotating with the shaft 56, thus locking the drum 58 to the said shaft and causing it to be rotated therewith. When the drum 58 has made a complete revolution with the shaft 56, thus bringing the heel 73 of the clutch pawl 60 to its first position, the pawl 72 will have been returned to its first position by means of the spring controlled shaft 71 so as to engage said heel and raise the pawl 60 from its engagement with the tooth 61. Upon the advance of another box and its engagement with the trigger 69, the movement of the trip bar will repeat the operation of the clutch pawl 60 hereinabove described.

mittently operated sprocket chain 40 by means of which the boxes are advanced over the conveyor when applying the lids thereto, is best shown in Figure 4. It is suitably mounted in the frame structure and is provided at its upper end with a bevelled gear 41^b. Said bevelled gear meshes with a bevelled gear 41^c mounted on a horizontal shaft 82, which is driven by a sprocket chain 83 and sprocket wheels 83^a and 83^b, respectively, mounted on the drum 58 and the shaft 82.

Adjacent to the cam groove 63 a sprocket wheel 74 is fixed to the drum 58. Said sprocket wheel is connected by a chain 75 to a sprocket wheel 76 fixed to a horizontal shaft 77 located below and extending parallel to the axis of the drum 58, transversely of the conveyor belt 21 and suitably mounted in the frame. The shaft 77 has fixed to it a cam 78 (see Figures 2, 4 and 11) which is adapted to engage a roller on a horizontal, longitudinally reciprocable spring controlled rod 79, suitably mounted and guided for movement on the frame by rollers 80, as shown in Figure 11. Said cam is rotatable in the direction indicated by the arrow in Figure 11. The rod 79 is operatively connected to a head 81 (see Figures 2 and 3) which carries the horizontal slide plate 27 which, in its normal position, retains the stack of lids 25 in the chute 24, as heretofore described. The sprocket wheels 74, 76 are designed in such ratio that there will be two rotations of the drum 58 to one rotation of the cam 78. As a result, there will be but a single operation of the said slide plate for two operations of the trip bar 68 and of the pusher bar 45.

The cam 78 is also associated in operative relation with a rock arm 34^b (see Figure 11) fixed to a rock shaft 34^a, suitably mounted in the frame, and to which the swinging spanker arms 34 are fixed, said arms operating immediately after a pair of lids has been discharged from the chute 24. The cam 78, as shown in Figure 11, is designed to operate the rock arm 34^b immediately after it has actuated the rod 79, which is connected to the discharge slide plate 27. Thus said arms 34 will also operate but once for two operations of the trigger bar 68.

To prevent back lashing and to maintain the drum 58 in the position in which it is arrested, said drum is provided with a cam disc 85, having a cam shoulder 86 which is engaged by a roller 87 on a spring controlled brake arm 88 (see Figure 3). Said brake arm is suitably pivoted above the drum at 89 on a frame member.

The downwardly and forwardly inclined plate 46 with the yielding fingers 50, to telescope the rear end of the lid down over the rear end of the box, is carried towards the rear (see Figures 1, 2 and 3) where it is connected to a crank pin 47 fixed to a crank arm 48^a on a stud 48 fixed to the frame member 49. By adjusting the position of the crank arm forwardly or rearwardly, the fingers 50 may be brought to the necessary position to properly perform their function.

As it may happen by reason of some failure of the mechanism for covering the boxes, that a box may pass on the conveyor beyond the rollers 51 without the lid being properly closed down on the box, or without a lid, or with one of the flaps of flies of the box not folded down on the box—I prefer to provide automatic means for stopping the machine in case of such occurrence. To this end I provide a supplementary pawl 72^x (see Figures 3, 5 and 12) loosely mounted on the rock

shaft 71, with a bell-crank arm 72^y connected by a link 72^w to the movable member 72^v of a solenoid 72^u. 90 indicates the field of said solenoid which is normally open. 90^a indicates a switch in the circuit adapted to be closed by a swinging transverse bar 91 located at some point beyond the box covering mechanism shortly above the level of the path of the top of the boxes. If the lids are properly closed on the boxes, the boxes are carried on the conveyor belt beyond said bar 91 and without interference therewith. When, however, a box comes along with a lid improperly applied or with something sticking up above the level of the box, the swinging bar 91 will be struck by said bar and will act to close the switch 90^a. This causes the energization of the field of the solenoid 72^u, whereupon the bell-crank arm 72^y will be operated by the solenoid to shift the pawl 72^x (to the left as shown in Figures 3 and 6), to bring said pawl into the path of the heel 73 of the clutch pawl 69. This will act to hold the clutch pawl from clutching engagement with the shaft and prevent operation of the mechanism, notwithstanding that the pawl 72 has been operated by the trip bar 68 to release such clutch pawl.

While in describing a preferred embodiment of my invention, I have referred to many details of mechanism and arrangement of parts, it is to be understood that the invention is not limited thereto, except as may be pointed out in the appended claims.

I claim as my invention:

1. In a box covering machine, in combination with a conveyor for boxes, means for delivering lids in succession in a rearwardly and upwardly inclined position above and proximate to said conveyor, intermittently operating, forwardly moving means for advancing a box on said conveyor, a ramp bar associated with said box advancing means in line with a near side of the lids delivered to said conveyor, means associated with said conveyor for guiding the boxes into position over against said ramp bar, a pusher bar for laterally displacing said boxes on said conveyor to bring them into engagement with said ramp bar and with said box advancing means, a trigger projecting into the path of boxes carried on the main conveyor, a continuously rotating shaft, a drum mounted on said shaft, a clutch intermediate said drum and said shaft, operating mechanisms severally connecting in predetermined timed relation said drum with said pusher bar, said box advancing means and said lid delivering means, and devices operatively connecting said clutch and said trigger adapted to actuate said clutch when said trigger is engaged by a box on said conveyor.

2. In a box covering machine, in combination with a main conveyor for boxes, means for delivering lids in succession to a rearwardly and upwardly inclined position above and proximate to said conveyor, an intermittently operable auxiliary conveyor for engaging and advancing a box relative to said conveyor, a ramp bar associated with said auxiliary conveyor in line with a near side of the lids delivered to said main conveyor, means associated with said main conveyor for guiding the boxes into position over against said ramp bar, a pusher bar for laterally displacing said boxes on said conveyor to bring them into engagement with said ramp bar and with said auxiliary conveyor, a trigger projecting into the path of boxes carried on the main conveyor, a continuously rotating shaft, a drum mounted on

said shaft, a clutch intermediate said drum and said shaft, operating mechanisms severally connecting in predetermined timed relation said drum with said pusher bar, said auxiliary conveyor and said lid delivering means, and devices operatively connecting said clutch and said trigger adapted to actuate said clutch when said trigger is engaged by a box on said main conveyor.

3. In a box covering machine, in combination with a conveyor for boxes, a chute above said conveyor containing lids disposed in pairs, with the top lid of each pair having its sides and rear end embracing the sides and rear end of the bottom lid, means for ejecting each pair of said lids in succession to bring them to a rearwardly and upwardly inclined position above and proximate to said conveyor, intermittently operating, forwardly moving means for advancing a box on said conveyor, a ramp bar associated with said box advancing means in line with the proximate side of the lids delivered to said conveyor, means associated with said conveyor for guiding the boxes into position over against said ramp bar, a pusher bar for laterally displacing said boxes on said conveyor to bring them into engagement with said ramp bar and said box advancing means, a trigger projecting into the path of boxes carried on said conveyor, a continuously rotating shaft; a drum mounted on said shaft, a clutch device intermediate said drum and said shaft, mechanisms severally connecting said drum with said pusher bar, said box advancing means and said lid ejecting and disposing means in the ratio of two operations of said pusher bar and said box advancing means to one operation of said lid ejecting and disposing means, and devices operatively connecting said clutch and said trigger adapted to actuate said clutch when said trigger is engaged by a box on said conveyor.

4. In combination with a stack of lids disposed in pairs, one above the other, with the top lid of each pair having its sides and rear end embracing the sides and rear end of the bottom lid, a vertical chute adapted to contain said stack of lids, a movable support for the front end of said stack, an auxiliary fixed support spaced below said movable support less than the depth of a lid, a conveyor for advancing boxes in a plane below said chute, means for reciprocating said movable support for momentarily withdrawing it from below said stack and then returning it thereto, said movable support acting on its return to eject the bottom pair of lids from said auxiliary support, means for receiving and supporting the rear end of the ejected pair of lids in a rearwardly and upwardly inclined position above said conveyor, and a stop forward of said last named means for preventing the top lid of a pair from being dropped towards said conveyor until the bottom lid has been carried away by a box advancing on said conveyor engaged within its front end.

5. In combination with a stack of lids disposed in pairs, one above the other, with the top lid having its sides and rear end embracing the sides and rear end of the bottom lid, a vertical chute adapted to contain said stack of lids, a movable support for the front end of said stack, an auxiliary fixed support spaced below said movable support less than the depth of a lid, a conveyor for advancing boxes in a plane below said chute, means for reciprocating said movable support for momentarily withdrawing it from below said stack and to then return it thereto,

said movable support acting on its return to eject the bottom pair of lids from said auxiliary support, a support to receive the rear end of the ejected pair of lids, a device for striking the top one of said lids to bring the pair into a rearwardly and upwardly inclined position above said conveyor, and a stop forward of said support for preventing the top lid of a pair from being dropped towards said conveyor until the bottom lid has been carried away by a box advancing on said conveyor and engaged within its front end.

6. In combination with a stack of lids disposed in pairs, one above the other, with the top lid having its sides and rear end embracing the sides and rear end of the bottom lid, a vertical chute adapted to contain said stack of lids, a movable support for the front end of said stack, an auxiliary fixed support spaced below said movable support less than the depth of a lid, a conveyor for advancing boxes in a plane below said chute, means for reciprocating said movable support for momentarily withdrawing it from below said stack and to then return it thereto, said movable support acting on its return to eject the bottom pair of lids from said auxiliary support, a downwardly and forwardly inclined support to receive the rear end of the ejected pair of lids, a device for striking the top one of said lids to bring the pair into a rearwardly and upwardly inclined position above said conveyor, and a stop forward of said support for preventing the top lid of a pair from being dropped towards said conveyor until the bottom lid has been carried away by a box advancing on said conveyor and engaged within its front end.

7. In combination with a stack of lids disposed in pairs, one above the other, each pair comprising a top lid and a bottom lid, with the top lid having its sides and rear end embracing the sides and rear end of the bottom lid, a vertical chute adapted to contain said stack of lids, a horizontal reciprocable ejector plate normally disposed below said chute under the front end of the bottom lid in said stack, a fixed plate disposed below said ejector plate and adapted to arrest the front end of a pair of lids when released by said ejector plate, a conveyor for advancing boxes in a plane below said chute, means for reciprocating said ejector plate to withdraw it from supporting position below said stack and to then return it thereto, said ejector plate acting on its return to strike and eject the bottom pair of lids from said fixed plate, a downwardly and forwardly inclined plate located above said conveyor rearwardly beyond said chute adapted to receive and support the rear ends of a pair of lids when thus ejected, a stop forward of said inclined plate for temporarily arresting the top lid of a pair and preventing it from being carried away with the bottom lid of said pair when said bottom lid is carried forward by a box advanced on the conveyor with its front end engaged within the front end of said lid, and means for telescoping the rear end of said lid down upon the rear end of said box as it is carried away on said conveyor.

8. In combination with a stack of lids disposed in pairs, one above the other, each pair comprising a top lid and a bottom lid, with the top lid having its sides and rear end embracing the sides and rear end of the bottom lid, a vertical chute adapted to contain said stack of lids, a horizontal reciprocable ejector plate normally disposed below said chute under the front end

of the bottom lid in said stack, a fixed plate disposed below said ejector plate and adapted to arrest the front end of a pair of lids when released by said ejector plate, a conveyor for advancing boxes in a plane below said chute, means for reciprocating said ejector plate to withdraw it from supporting position below said stack and to then return it thereto, said ejector plate acting on its return to strike and eject the bottom pair of lids from said fixed plate, a downwardly and forwardly inclined plate located above said conveyor rearwardly beyond said chute adapted to receive and support the rear

ends of a pair of lids when thus ejected, a stop forward of said inclined plate for temporarily arresting the top lid of a pair and preventing it from being carried away with the bottom lid of said pair when said bottom lid is carried forward by a box advanced on the conveyor with its front end engaged within the front end of said lid, means for telescoping the rear end of said lid down upon the rear end of said box, and means operating to bear down on said lid and close it on the box as said box is carried away on the conveyor. 5 10
